United States Patent Office

Des. 201,563
Patented July 6, 1965

201,563

FOOTED TUMBLER OR SIMILAR ARTICLE

Robert Alexander Wilkin, London, England, assignor to
Peter Pan Productions Limited, London, England, a
British company

Filed July 29, 1964, Ser. No. 81,053

Claims priority, application Great Britain Feb. 19, 1964

Term of patent 14 years

(Cl. D36—8)

Fig.1.

The footed tumbler or similar article is preferably opaque and is circular when viewed in plan. The side not shown is plain.

I claim:

The ornamental design for a footed tumbler or similar article, substantially as shown and described.
